UNITED STATES PATENT OFFICE.

JOHN H. EMPSON, OF LONGMONT, COLORADO.

PEA-SHELLING MACHINE.

SPECIFICATION forming part of Letters Patent No. 773,858, dated November 1, 1904.

Application filed August 3, 1903, Serial No. 167,994. (No model.)

To all whom it may concern:

Be it known that I, JOHN H. EMPSON, a citizen of the United States, residing at Longmont, in the county of Boulder and State of Colorado, have invented certain new and useful Improvements, 5 in Pea-Shelling Machines, of which the following is a specification.

The machine represented in the accompanying drawings in its general features and mode 10 of operation is similar to that set forth in my previous patents. In the present instance my invention relates to important improvements which obviate certain serious difficulties which have been encountered in a long 15 acquaintance with the machine and its operation.

The objects of the invention are, first, to provide a mechanism for driving the outer cylinder which overcomes the unsymmetrical 20 uneven motion resulting from the means formerly employed; second, to provide an adequate support for the traveling chaff-conveying apron which is simple in construction and offers minimum resistance to passage of said apron 25 over its supporting-surface; third, to provide a means for securing the screen-frames to the outer drum in such manner as to permit them to be removed easily and such that said frames are held firmly in place when the machine is 30 in operation; fourth, to provide a device for guiding the vines after their discharge onto a slatted rack at the discharge end of the machine; fifth, to provide a means whereby the loose peas remaining in the mass of vines after 35 their discharge from the drum are freed and recovered, thereby avoiding a considerable loss of peas; sixth, to provide a simple and effective method for driving the apron which separates the remaining loose peas from the 40 vines after their discharge from the drum; seventh, to provide a simple, inexpensive, and rigid construction for the inner drum; eighth, to provide a means for fastening the rubber paddles to the faces of the inner drum 45 which overcomes the troublesome lack of rigidity which has been heretofore experienced; ninth, to provide a simple, inexpensive, and rigid construction for the rollers about which the traveling aprons move; tenth, to provide 50 a device within the outer drum which pre-

vents the too - rapid progress of the vines through said drum, thereby opposing the tendency of the vines to carry through with them peas which have been hulled, and thereby also subjecting them to a more thorough threshing by the paddles on the inner rotating drum. I attain these objects by the means illustrated in the accompanying drawings.

In the drawings, Figure 1 represents a partial vertical longitudinal section and side elevation of such parts as it is necessary to show to give an understanding of the improvements. Fig. 2 is a plan view and an end elevation of the improved apron-support. Fig. 3 is a partial vertical section of the angle-iron which is used 60 to prevent the too-rapid advance of the vines through the drum. Fig. 4 represents a partial transverse vertical section and end elevation of the machine along the line *a a* of Fig. 1, certain parts being omitted for the purpose of disclosing others. Fig. 5 represents a side elevation of the body of the machine, showing the improved device for driving the outer drum. Fig. 6 is a sectional view of the shell 65 of the outer drum, showing the improved means for attaching the screen-frames. Fig. 7 represents a longitudinal sectional view of the inner drum, showing an improved construction. Fig. 8 and Fig. 9 represent the rubber - covered paddle and in section the 70 means for securing it to the boards of the inner drum. Fig. 10 represents in end elevation and partial longitudinal section the vine-beater. Fig. 11 represents in section the 75 construction of the rollers about which the aprons travel.

The general mode of operation of the machine illustrated in the accompanying drawings is similar to that of former patents—namely, No. 546,085, dated September 10, 90 1895, and No. 604,377, dated May 24, 1898—granted to myself.

It is to be understood that as regards the inventions herein claimed I do not confine myself in their application to the specific type of 95 pea-huller herein described, since they may to advantage be applied to any pea-hulling machine which employs the parts to which my inventions appertain.

Referring to the drawings, A represents the 100

two bearing-surfaces upon the periphery of the slowly-rotating outer drum, which rest upon and rotate concurrently with the two pairs of pulleys B. (Shown in Figs. 4 and 5.) 5 C represents the two shafts upon which the said pulleys are fixed.

D represents two annular racks situated on the periphery of the outer drum, which are geared with two pinions E, which are fixed 10 on one of the shafts C, bearing two of the pulleys B B. One of these pinions E is geared with a pinion 2 upon the shaft 1, which shaft receives rotary motion, through chain and sprocket, from the shaft O of the inner rapidly-revolving drum. It is to be understood, however, that I do not limit myself to this 15 particular means of driving the shaft C, for any convenient connection with the power-shaft of the machine would answer as well. 20 F represents the longitudinal supports for the support of the traveling chaff-conveying apron 3, the upwardly-traveling portion of which is in contact at its lower face with the transverse members G of the support.

25 H represents reinforcing-plates fixed beneath the transverse members G.

I represents the beveled ends of the transverse members G, presenting to the traveling apron a curved surface which minimizes friction 30 and wear on the apron.

J is an iron T-bar extending lengthwise within the outer drum, to which are attached the screen-frames 7 of said drum. 4 represents stud-bolts fixed at convenient intervals 35 in said T-bar, bearing each a thumb-screw 5 and a washer 6, which is of sufficient size to engage both of said frames 7, abutting along the line of the T-bar J.

K represents two guides in the form of a 40 bottomless trough attached in any convenient manner to the framework of the machine so arranged as to guide the vines upon their discharge from the drums onto any appliance, such as the slatted rack 8, which is placed 45 below to receive them. This device possesses the advantage of doing away with the hitherto troublesome radial discharge and confining the vines to that particular part of the machine where they are next to be dealt with.

50 L is a rapidly-rotating system of beaters driven in any convenient manner, upon which the discharged vines fall and are thoroughly beaten, permitting any peas therewith to fall upon whatever device may be below to receive 55 them—as, for example, the straw-conveying apron 9.

M is a belt, of any suitable material, actuated by a driving-pulley 10 on a shaft which receives rotary motion from any convenient 60 source. This belt M passes over idlers 11 and engages another pulley 12 on the shaft of the roller about which moves the straw-conveying apron 9. This device possesses the advantage of extreme simplicity and does 65 away with the bevel-gearing, which heretofore

was so troublesome because of its tendency to become clogged by the refuse of the machine. The necessity for the bevel-gearing is obviated by the adoption of this device, and a simple method for driving the straw-conveying apron 70 is secured.

N represents the spiders which form the framework of the inner beating-drum or core of the machine. These spiders N are seated and set-screwed upon a shaft O, which is journaled on the framework. These spiders are adapted to receive and maintain in position near their outer edges and between adjacent pairs the plates 13, of any suitable material, which when in position form complete the surface of the drum. Extending longitudinally through the drum from end to end are the through-bolts P, designed to hold the spiders firmly in place and to give rigidity to the drum. The heads and nuts of these through-bolts bear 80 upon the exterior faces of the end spiders of the drum.

In Figs. 9 and 10 Q is a reinforcing-plate placed beneath each paddle upon the inner face of the drum. The through-bolt 15 passes 90 through this plate, thence through the plate 13 of the drum, thence through the base of the paddle 14, all being secured by a nut bearing upon the upper face of the base of the paddle 14. The advantage of this means for attaching the paddle lies in the rigid fixation made possible by the metal reinforcing-plate Q. Formerly because of the fact that the paddles were not firmly attached to the faces of the drum great difficulty was experienced in 95 maintaining a proper impact between the paddles and the pea-pods. The proper adjustment of this impact is of the utmost importance.

In Fig. 11, R represents spiders which are 105 seated and set-screwed upon a shaft S. These spiders (similar to those in the inner drum, see N) are adapted to receive and maintain in position near their outer edges between adjacent pairs plates T, of any suitable material, which 110 form complete the surface of the roller. This construction permits the use of a roller of considerable radius, which is most desirable and which at the same time is light and runs easily with slight expenditure of power.

V (see Figs. 1 and 3) is a circular angle-iron placed within the outer drum adjacent to its inner surface which checks the advance of the pea-vines as they move toward the discharge end of the machine. It has been found heretofore that when the vines are forced through the outer drum by the action of obliquely-set paddles on the inner rotating drum said vines progress with such speed that they carry with them a great many loose peas, which 125 are either lost or recovered with difficulty after the vines have been discharged from the drums. This angle-iron, however, impedes the advance of the vines and subjects them to a prolonged agitation by the beating-paddles 130

- on the inner rotating drum, by which the loose peas are freed and permitted to fall through the perforations in the outer drum instead of being carried onward by the rush of the vines.
- 5 In the operation of this machine the driving-gear is so arranged and positioned that the inner drum W and the outer drum X will be rotated at relatively different rates of speed for purposes well understood in this art, and 10 as the vines are passed into the feed end Y they are thoroughly threshed by the paddles 14 upon the periphery of the inner rapidly-rotating drum W, the shelled peas falling through the perforations in the outer drum X.
- 15 Said paddles 14 are arranged obliquely in the form of a spiral, so that as they revolve they force the vines toward end Z of the machine. Thrust out at the discharge end Z the vines, conducted by the guides K, fall upon the slatted rack 8, whence they fall upon the vine-beater L, where they are thoroughly agitated, the shelled peas confined therein being permitted to fall upon the apron 9, down the face of which they roll, while the vines are conveyed upwardly by the apron and dumped over the roller S. The peas which fall through the perforations in the outer drum X strike the endless traveling apron 3 and roll down its surface into a trough. Such chaff as falls 25 through with the peas adheres to the surface of the apron and is removed by the brush 15.
- Having described my invention, what I claim as new, and desire to secure by Letters Patent, is—
- 30 1. A pea-shelling machine having, in combination, an inclined adjustable traveling apron, and a support for the upper run of said apron comprising longitudinal rails, and a plurality of transverse spaced inclined slats secured thereto with their ends projecting beyond the longitudinal rails, the whole being positioned to permit easy contact between the upper surfaces of said slats and the under surface of the upper run of said apron, said 35 slats being reinforced upon their under sides near their ends, and having their ends beveled to present curved surfaces to the under side of said apron, whatever its adjustment, at the points of initial and final contact therewith.
2. A pea-shelling machine having, in combination, a drum which discharges the depleted vines through one end, a rack which receives the discharged vines, and conveying-guides above said rack at opposite sides of the discharge end of said drum which direct the vines to the rack.
3. A pea-shelling machine having, in combination, a hulling-drum, and means for liberating peas from the masses of vines after their discharge from said drum, said means comprising a rapidly-rotating beater below said drum and a separator below said beater, the vines being dropped from said drum upon said beater and being agitated thereby, the freed peas and depleted vines then falling upon said separator which consists in a smooth-surfaced inclined traveling apron which carries the vines upward and dumps them, the freed peas rolling down the inclined surface of said apron.
4. A pea-shelling machine having an inner rotating drum comprising a plurality of spiders including end spiders and intermediate spiders; a shaft upon which said spiders are fastened; each pair of said spiders being adapted to receive between them and maintain in position near their outer edges plates which form complete the surface of said inner drum; longitudinal through-bolts, extending the entire length of said drum and through all the spiders, by which said spiders are held firmly in position and said drum is made rigid; the heads and nuts of said through-bolts bearing upon the exterior faces of the said two end spiders.
5. A pea-shelling machine having a traveling apron, and rollers about which said apron moves, consisting of a plurality of spiders including end spiders and intermediate spiders; a shaft upon which said spiders are fastened; each pair of the said spiders being adapted to receive between them and maintain in position near their edges plates which form complete the surface of said roller.
6. A pea-shelling machine having, in combination, a slowly-rotating outer hulling-drum; a rapidly-rotating inner beating-drum, having means for feeding vines through said outer drum; and means for retarding the progress of said vines during their travel through said outer drum, consisting of an annular rim secured to the inside of said outer drum and bearing an annular flange extending inwardly into said outer drum toward said inner drum.

In witness whereof I have hereunto signed my name in the presence of two subscribing witnesses.

JOHN H. EMPSON.
